H. A. MIKSCH

TOY GUN

Filed March 23, 1926

Inventor
Herman A. Miksch

By *Watson E. Coleman*
Attorney

UNITED STATES PATENT OFFICE.

HERMAN A. KIKSCH, OF CUSHING, OKLAHOMA.

TOY GUN.

Application filed March 23, 1926. Serial No. 86,767.

This invention relates to toy guns and more particularly to a toy gun intended for use in shooting rubber bands.

An important object of this invention is to provide a device of this character, the construction of which is such that the velocity of the projectile may be regulated to suit the desires of the user.

A further object of the invention is to provide a device of this character which includes means for conveniently supporting a plurality of rubber bands for use thereon.

These and other objects I attain by the construction shown in the accompanying drawing, wherein for the purpose of illustration is shown a preferred embodiment of my invention and wherein:

Figure 1 is a side elevation of a toy gun constructed in accordance with my invention;

Figure 2 is a plan view thereof;

Figure 3 is an enlarged fragmentary side elevation partially in section.

Referring now more particularly to the drawing, the numeral 10 generally designates a barrel section and 11 a stock section. A convenient method of producing the barrel and stock section is by employing a bar which forms the barrel section and which at the end of the barrel section is offset downwardly, as at 12, to form the top of the stock and then bent back to form the bottom of the stock and finally joined to the offset portion 12, as at 13. The barrel adjacent its rear end has formed therethrough a vertically extending bore 14, through which is extended a bolt 15, the upper end of which normally projects slightly above the upper surface of the barrel section 10.

Pivoted to the forward end of the stock at the under surface thereof is a bell crank lever 16, one arm of which is pivotally connected with the lower end of the bolt, as at 17, and the opposite arm of which projects downwardly and forms a trigger 18. A spring 19 connects the first named arm of the lever with the barrel 10 and tends to maintain the bolt in its proper position. Upward movement of the bolt is limited by a transverse pin 20 which engages the under surface of the barrel. The trigger mechanism may be enclosed by a suitable guard 21, if so desired.

The upper surface of the barrel is provided at spaced points with shoulders 22, 23, 24 facing toward the forward end of the

barrel section. These shoulders may be conveniently produced by employing a small bar 25 and directing one end of this bar through a bore 26 formed in the barrel section. At a point spaced above the upper surface of the barrel, the bar is then bent so that it inclines rearwardly and downwardly to provide an inclined rear face for the shoulder element and the terminal portion thereof is extended at an angle, as at 27, to pass through a second opening 28 formed in the barrel. At the under surface of the barrel, a cleat 29 is provided to act as a magazine for holding the bands 30 which are to be employed. This cleat is preferably produced by employing a small metal bar and reverting the end portions of the bar upon the bar, as at 31, the terminals of these reverted end portions being extended in parallel relation and at right angles to the bar, as indicated at 33, and passed through openings formed in the barrel section 10. These parallel portions are spaced apart a distance slightly greater than the normal length of 80 band which is to be employed with the gun so that the band is under slight tension when applied thereto.

It will, of course, be obvious that by engaging the band with a stop 23 or 24, the velocity of the band when released will be much greater than if the band is engaged with the stop 22. It will also be obvious that the device may be readily and cheaply produced and durable and efficient in service.

Since this construction is obviously capable of a certain range of change and modification without materially departing from the spirit of the invention, I do not limit myself to such specific structure except as hereinafter claimed.

I claim:

1. A toy gun including a barrel section having spaced shoulders facing toward the muzzle end thereof and the rear faces of said shoulders inclining downwardly toward the rear end of the stock adapted to selectively receive one end of an elastic band and a trigger operated bolt at the stock end of the barrel adapted to receive the opposite end of the band.

2. A toy gun including a barrel section having spaced shoulders facing toward the muzzle end thereof and adapted to selectively receive one end of an elastic band and a trigger operated bolt at the stock end of

- the barrel adapted to receive the opposite end of the band, each of said shoulders comprising a bar having the forward end thereof directed through a vertically extending opening in the barrel, said bar at points spaced above the barrel being bent rearwardly and downwardly and having its rear end directed through a second opening formed in the barrel.
- 10 3. A toy gun including a barrel section having spaced shoulders facing toward the muzzle end thereof and adapted to selectively receive one end of an elastic band and a trigger operated bolt at the stock end of
- 15 the barrel adapted to receive the opposite end of the band, the under surface of the barrel having a cleat for the reception of the additional bands, said cleat comprising a bar paralleling the barrel and having its under portions reverted thereon, the terminals of said end portions being extended in parallel relation and at right angles to
- 20 in testimony whereof I hereunto affix my signature.
4. A toy gun including a barrel section 25 having spaced shoulders facing toward the muzzle end thereof and adapted to selectively receive one end of an elastic band and a trigger operated bolt at the stock end of the barrel adapted to receive the opposite 30 end of the band, the under surface of the barrel having a cleat for the reception of the additional bands, said cleat comprising a bar paralleling the barrel and having its 35 under portions reverted thereon, the terminals of said end portions being extended in parallel relation and at right angles to the normal length of the band employed.
- 40
